CLAIM

I claim the ornamental design for a semiconductor memory card recorder with radio tuner, as shown and described.

DESCRIPTION

FIG. 1 is a top perspective view of a semiconductor memory card recorder with radio tuner of the present invention;

FIG. 2 is a front view thereof;

FIG. 3 is a first side view thereof;

FIG. 4 is a second side view thereof;

FIG. 5 is a top view thereof;

FIG. 6 is a bottom view thereof;

FIG. 7 is a rear view thereof; and,

FIG. 8 is a top perspective view thereof shown in an environmental use, wherein the displayed characters shown in broken lines form no part of the claimed design.
